UNITED STATES PATENT OFFICE

119,648

DESIGN FOR A PICTURE VIEWER CASE

Hugo Bernzott, Chicago, Ill., assignor to The Bell & Howell Company, Chicago, Ill., a corporation of Illinois

Application December 11, 1939, Serial No. 38,825

Term of patent 14 years

To all whom it may concern:

Be it known that I, Hugo Bernzott, a citizen of the United States, residing at Chicago, in the county of Cook and State of Illinois, have invented a new, original, and ornamental Design for a Picture Viewer Case, of which the following is a specification, reference being had to the accompanying drawing, forming a part thereof.

In the said drawing—

Figure 1 is a perspective view of a picture viewer case, embodying my new design; Figure 2 is a front elevation of the same; Figure 3 is a top plan view of the same; and Figure 4 is a side elevation of the same.

I claim:

The ornamental design for picture viewer case, as shown.

HUGO BERNZOTT.
